STEERING POST MOUNTING FOR TOY VEHICLES

Filed March 12, 1929

Inventor

M. S. Furman

By Clarence O'Brien
Attorney

UNITED STATES PATENT OFFICE

MAXWELL STEELE FURMAN, OF MORGANTOWN, WEST VIRGINIA

STEERING-POST MOUNTING FOR TOY VEHICLES

Application filed March 12, 1929. Serial No. 346,380.

The present invention relates to toy vehicles and more particularly to mountings for the steering post of the vehicle.

One of the important objects of the invention is to provide a steering post for the vehicle capable of being steered by means of a pivoted handle adapted to extend in a position either forwardly of the vehicle enabling the same to be steered while being drawn, or which handle may extend vertically above the frame of the vehicle enabling the occupant of the vehicle to steer the same.

A further important object of the invention is to provide novel means for rotatably attaching the upper end of the steering post to the vehicle frame.

An additional object is to provide a device of this character of a simple and practical construction, which is strong and durable, which enables the same to be manufactured at a relatively low cost and which is otherwise well adapted for the purposes for which the same is intended.

Other objects and advantages reside in the special construction, combination and arrangement of the various elements forming the invention as more fully hereinafter described and claimed, reference being had to the accompanying drawings forming part hereof, wherein like numerals refer to like parts throughout, and in which:

Figure 1 is a top plan view of the forward end of a vehicle frame showing the relative position of the steering post with respect thereto,

Figure 2 is a vertical longitudinal sectional view therethrough, and

Figure 3 is a front elevational view thereof.

Referring now to the drawings in detail, wherein for the purpose of illustration I have disclosed a preferred embodiment of the invention, the numeral 5 designates generally a vehicle frame, which is preferably constructed of metal and of a channel shaped formation at its under side.

The forward end of the frame is recessed longitudinally as shown at 6 and beneath the frame, at the inner end of the recessed portion, is positioned a tubular steering post 7 having its upper end formed with an annular

flange 8 for resting against the under side of the frame 5.

The upper end of the post 7, at one side thereof, is formed with a slotted opening 9 which also extends through the flanged portion 8 at one side thereof. The width of the slotted opening 9 is substantially equal to the width of the recess 6 of the frame.

An annular flange support 10 is positioned at the under side of the frame 5 and is formed with a central opening 11 through which the post 7 is inserted with the flange 8 resting upon the upper surface of the flange support 10, as more clearly illustrated in Figure 2 of the drawings.

One side of the flange support 10 is also formed with a slotted opening 12 extending from the central opening 11 of the outer edge of the support and of a width corresponding to the width of the recess 6 and the slotted opening 9 of the post. The outer annular edge of the flange support 10, is offset from its central portion, as shown at 13 and is adapted to rest against the surface of the under side of the frame for spot welding or otherwise securing thereto while the central portion of the flange support is disposed in spaced relation from the under side of the frame a sufficient distance to permit the free rotation of the flange 8 between the support and the frame.

A bolt 14 extends transversely of the post 7, below the lower edge of the frame and adjacent the lower edge of the slotted opening 9 and upon which a handle or tongue 15 is pivotally mounted at one end.

The tongue is adapted to extend outwardly through the slotted opening 9 either forwardly of the vehicle, or when the post is in a position for the registering of the slotted opening 9 with the recess 6, the tongue or handle may be extended vertically into a position above the frame, as indicated by the dotted line of Figure 2 of the drawings.

The lower end of the post 7 is forked as shown at 16 for attaching to the front wheels of the vehicle whereby to permit the steering of the same in a manner well known in the art.

It will be apparent from the foregoing that

the construction thus provided enables the steering post to be securely attached in position to the frame of the vehicle and at the same time enables the free rotation thereof for steering the front wheels of the vehicle through the manipulation of the tongue or handle 15.

It is obvious that my invention is susceptible to various changes and modifications in construction without departing from the spirit of the invention or the scope of the appended claims, and I accordingly claim all such forms of the device to which I am entitled.

15 Having thus described my invention, what I claim as new is:

1. A steering post mounting for vehicles comprising in combination, a vehicle frame having a recess extending inwardly of its forward edge, a steering post positioned beneath the frame at the inner end of said recess, a flange formed at the upper edge of said post, a flange support secured to the under side of the frame with a portion thereof disposed in underlying relation with respect to said flange whereby to secure the post for rotation beneath the frame, and a handle pivotally attached to the post, said flange support having a slotted opening registering with the recess whereby to receive the handle for extending above the frame.

2. A steering post mounting for vehicles comprising in combination, a vehicle frame having a recess extending inwardly of its forward edge, a steering post positioned beneath the frame at the inner end of said recess, a flange formed at the upper edge of said post, a flange support secured to the under side of the frame with a portion thereof disposed in underlying relation with respect to said flange whereby to secure the post for rotation beneath the frame, said post having a slotted opening formed in one side thereof and extending through the flange, a handle pivotally attached to the post for movement inwardly of the slotted opening into a position longitudinally of the post, said flange support also having a slotted opening in alignment with the recess whereby to receive the handle for extending above the frame upon the registering of the respective openings.

In testimony whereof I affix my signature.
MAXWELL STEELE FURMAN.
